UNITED STATES PATENT OFFICE.

WILLIAM EIERMANN, OF BROOKLYN, NEW YORK.

BORING SPADE.

Application filed January 20, 1921. Serial No. 438,700.

To all whom it may concern:

Be it known that I, WILLIAM EIERMANN, a citizen of the United States, residing at Brooklyn, in the county of Kings and State 5 of New York, have invented certain new and useful Improvements in Boring Spades; and I do declare the following to be a full, clear, and exact description of the invention, such as will enable others skilled in the art 10 to which it appertains to make and use the same.

This invention relates to an improved boring spade which is especially designed to be used by plumbers. It is manually operated 15 and enables the plumbers to form a comparatively lengthy horizontal underground bore in which piping may be laid and thus obviates the necessity of undue excavation which oftentimes ties up traffic and is a great 20 deal more expensive as is well known.

Another object of the invention is to generally improve upon devices of this class by the provision of one of extreme simplicity and durability which is made up of few 25 readily disconnectible parts, thus enabling the use of different lengths of handles, and also permitting the use of different lengths of blades.

Other objects and advantages of the invention will be apparent during the course 30 of the following description.

In the accompanying drawings forming a part of this specification and in which like numerals are employed to designate like 35 parts throughout the same:

Figure 1 is an elevational view of a boring spade constructed in accordance with this invention, showing one way in which the same may be used.

Figure 2 is an enlarged top plan view of 40 the device.

Figure 3 is a side elevational view thereof.

Figure 4 is a central longitudinal section taken on the plane of the line 4—4 of Fig. 2.

Figure 5 is a transverse section taken on the plane of the line 5—5 of Fig. 2.

In carrying out the invention, I make use of a scoop-like blade 1 of any suitable length, and a handle 2 which, like the blade, 50 will vary in length according to the length of the bore to be formed, the two parts being connected together by a novel connector 3. While the connector 3 could be of some other construction, I prefer that it be in a 55 form of a casting, the same including a horizontal laterally curved attaching flange ex-

tending into the rear end of the blade 1 and engaging the inner surface of the latter at this end, and a curved rib or bead 5 against which the adjacent end of the blade abuts. 60 The casting further includes an integral vertically disposed inclined portion 6 disposed at the inner end of said attaching flange and being of a height to substantially close this end of the blade in the manner shown. Furthermore, the casting includes a laterally extending internally screw-threaded socket 7 into which the screw-threaded end of a handle 2 is extended and has screw-threaded engagement, this socket being eccentric to enable 70 easy handling of the device. If desired, a set-screw 8 may be extended through the socket 7 and against the handle to prevent accidental rotation of the latter and thus insure against disconnection of the same. 75 As before stated, it is desirable to have all of the parts of the device disconnectible from one another, and in view of this, I make use of bolts 9 for connecting the blade with the attaching flange 4. It may be stated here 80 that an ordinary length of gas pipe may be employed as a handle for the device.

Ordinarily, in laying piping from the street-main to a house, considerable excavation is necessary and in congested districts, 85 this is undesirable since it oftentimes ties up traffic for sometime and much expense is involved in this method of laying pipes. However, by making use of my novel boring spade, very little or no excavation is 90 necessary, as an underground horizontal bore formed with my spade will suffice for laying the pipes. In Fig. 1 of the drawing, I have disclosed one way in which the above result may be accomplished. By referring to this 95 figure, it will be seen that the letter W designates the wall of a building, such as can be worked on from inside of a cellar. At a desirable distance below the pavement P, a hole H is formed in this wall in any suitable 100 way, such as for instance by a chisel. Now, by properly manipulating the spade a horizontal bore B may be formed entirely beneath the pavement, or in fact, entirely beneath an ordinary street, thus overcoming 105 the necessity of excavating any part of the street whatsoever. As before stated, all of the parts of the spade are easily separated from one another and according to the length of the bore, different lengths of blades 110 and handles will be employed. The exact manner of manipulating the device need not

be set forth here, since this will be better understood from actually using it.

A careful consideration of the foregoing description taken in connection with the accompanying drawing, is thought to be sufficient to enable persons skilled in the art to which the invention relates to obtain a clear understanding of the same. Therefore, a more lengthy description is deemed unnecessary.

Doubtless, advantageous and effective results will be obtained from a device constructed in accordance with my ideas. However, I wish it to be understood that slight minor changes in the shape, size, and arrangement of parts may be resorted to without departing from the spirit of the invention or the scope of the subjoined claims.

I claim:

1. A tool of the class described comprising a substantially channel-shaped shovel blade, and a connector for a handle including a transversely curved attaching flange with which one end of the blade is detachably connected, and an integral angularly disposed portion extending across one end of the blade and constituting a back, whereby to form a scoop.

2. A tool of the class described comprising a blade of channel-shaped cross-section, a relatively long handle, a one-piece casting

forming a connecting member for the handle, said member including a transversely curved attaching flange telescoping into the inner end of the blade and bearing against the inner face thereof, a similarly curved rib on the underside of said flange for providing an abutment against which the adjacent end of the blade bears, a vertical and inclined wall or portion rising from and extending across the inner end of the blade to form a scoop, and a socket with which the adjacent end of said handle is detachably connected.

3. A tool of the class described including a one-piece casting constituting a connecting member for a handle, said casting embodying a transversely curved attaching flange adapted for connection with a transversely curved substantially channel-shaped shovel blade, an integral and inclined portion extending at right angles from said flange and constituting a back for said blade to form a scoop, a curved rib on the under side of the flange at the juncture thereof with said portion, said rib constituting an abutment against which the adjacent end of the blade is adapted to bear, and a laterally disposed integral socket for reception of the handle.

In testimony whereof I have hereunto set my hand.

WILLIAM EIERMANN.
